UNITED STATES PATENT OFFICE.

EDWIN F. WOLTHAUSEN, OF DULUTH, MINNESOTA.

GEOMETRIC COMPASSES.

1,263,182.

Specification of Letters Patent. Patented Apr. 16, 1918.

Application filed August 31, 1917. Serial No. 189,212.

To all whom it may concern:

Be it known that I, EDWIN F. WOLTHAUSEN, a citizen of the United States, residing at Duluth, in the county of St. Louis and State of Minnesota, have invented new and useful Improvements in Geometric Compasses, of which the following is a specification.

This invention is a compass attachment wherein the stationary point of the compass may be properly positioned and securely held against movement when drawing large circles or arcs.

One object of the invention is to provide an attachment for compasses wherein the stationary point may be accurately located and visible at all times and yet be retained in its original position.

Another object of the invention is to provide an attachment having a vacuum cup that is adapted to be attached to one of the legs of a compass and by means of an arm the vacuum cup is spaced from the point carried by the leg of the compass.

Broadly stated the invention comprises a vacuum cup having means to cause the cup to engage with a surface and an arm extending from the cup which arm is provided with means for engaging with the point of a compass.

One practical form of construction and assembly will be described and illustrated in the accompanying drawings, in which—

Figure 1 is a side elevation of a compass and the attachment.

Fig. 2 is a vertical sectional view of the vacuum cup and arm and

Fig. 3 is a top plan view of the vacuum cup and arm.

In the preferred embodiment about to be described, a black-board compass is shown having the legs 5 and 6. The legs may be pivotally connected together as indicated by the joint 7. The joint 7 may also include the handle 8. The joint 7 should preferably be made so that the legs may be frictionally held at any desired point of separation. As shown, the leg 5 has attached thereto a holder generally indicated at 9. This holder 9 may be formed of any suitable material and is preferably so constructed to hold a piece of chalk 10 therein. If desired the holder may be of the split or clamping type, the sections of which are held together by means of the clamping screw 11. The holder 9 thus provides for the adjusting piece of chalk 10.

The leg 6 may be provided with the usual stationary point, one form of which is indicated at 12. This point is preferably so constructed that it will engage with the center point of the arc or circle which the user desires constructed. The point 12 may be provided with a reduced cylindrical section 13 as shown. To coöperate with this reduced section 13, an arm 14 is employed that preferably extends at right angles thereto. To hold this arm 14 in its proper position it may be secured to the point 12 and in proper position relative to the reduced section 13 by means of clamping screws 15. These screws 15 may serve to hold a detachable section if so desired.

Any form of attachment may be utilized which will permit the arm 14 to rotate freely with respect to the point 12 and the reduced section 13. The other end of the arm 14 is provided with a suction cup 16 which may be of any usual type of construction. In the present instance the cup is provided with a depressed surface 17 upon its under side.

In order to hold the cup 16 in its proper position upon the arm 14, the cup is provided with suitable engaging means, one form of which is indicated at 18. One end of this engaging means extends beyond the surface of the cup and is preferably threaded at 19 as shown. The threaded portion 19 is adapted to engage with a suitable holder having threads formed therein which is carried by the arm 14.

As shown, the vacuum cup is attached to the under side of the arm 14. Mounted upon the upper side of the arm 14 is a knob 20 which as shown is provided with an upper flat face 21. It is preferred to make the vacuum cup 16 of circular form, and also to form the knob 20 in a similar manner.

The cup 16 is preferably formed of rubber so that it may readily adhere to more or less uneven surfaces. The knob 20 may be formed of any suitable material, and is employed for the purpose of pressing the cup into engagement with a surface to expel the air from beneath the vacuum cup 16. When this attachment is secured to a compass large arcs and circles may be drawn and the stationary point 12 will be maintained at its proper place. The point 12 may be located at the point of erection of the circle or arc, and as the vacuum cup is spaced from the point 12 the point is always visible.

The leg 6 is adapted to rotate in the arm

14 by means of the reduced section or portion 13, so that in the present illustration the leg 5 carrying the chalk 10 will rotate entirely around the attachment.

5 The leg 6 and the point 12 may be connected together by means of a joint 22 that will provide for more or less universal movement. Any type of joint may be used for this purpose.

10 What is claimed is:—

1. An attachment for compasses employed for drawing large geometrical figures, which comprises a vacuum cup adapted to be secured to a surface through atmospheric pressure, an arm extending from said cup, means for securing the arm to a leg of a compass to permit same to rotate with respect to the arm, the spacing of said cup from the leg to which it is attached providing for the visibility of the striking point of the figure during 20 construction.

2. The combination with a compass, of a vacuum cup, a laterally extending arm secured to said cup, a pointed element swiveled in said arm and means for pivotally securing 25 the pointed element to one leg of the compass.

3. The combination with a compass, of an arm having one end secured to one leg of the compass in a manner to permit of the rotation of said leg, a vacuum cup provided with 30 a threaded extension engageable with the opposite end of said arm, a securing element threadedly engaging said extension to hold the arm in position and having a relatively broad upper surface.

35 In testimony whereof I affix my signature.

EDWIN F. WOLTHAUSEN.
